UNITED STATES PATENT OFFICE.

TEGRAN M. SAMOUR, OF ROXBURY, MASSACHUSETTS.

DESIGN FOR A WIND-WHEEL.

53,469.

Specification for Design.

Patented June 17, 1919.

Application filed April 1, 1919. Serial No. 286,774. Term of patent 7 years.

To all whom it may concern:

Be it known that I, TEGRAN M. SAMOUR, a citizen of the United States, residing at Roxbury, in the county of Suffolk, State of Massachusetts, have invented a new, original, and ornamental Design for Wind-Wheels, of which the following is a specification, reference being had to the accompanying drawing, forming a part thereof.

The figure is a front elevation of the wind wheel, showing my new design.

I claim—

The ornamental design for a wind wheel as shown.

In testimony whereof, I hereunto affix my signature in the presence of two witnesses.

TEGRAN M. SAMOUR.

Witnesses:

JOHN W. RORKE,
JEAN M. DANIELSON.
